UNITED STATES PATENT OFFICE.

FRED L. MACKENZIE, OF BEVERLY, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed April 17, 1919. Serial No. 290,651.

To all whom it may concern:

Be it known that I, FRED L. MACKENZIE, a citizen of the United States, residing at Beverly, in the county of Essex and State 5 of Massachusetts, have invented certain Improvements in Fastening-Inserting Machines, of which the following description, in connection with the accompanying drawings, is a specification, like reference characters 10 on the drawings indicating like parts in the several figures.

This invention relates to fastening inserting machines and more particularly to machines of this class which provide means 15 for feeding the work and for locating fastenings with respect to the work during fastening inserting operations.

The invention is illustrated in connection with a machine designed to secure together 20 two pieces of work, as, for instance, a heel section and a half sole wherein the heel section is of different material from that present in the half sole, and in which the sections or pieces of work have been beveled edges 25 adapted to be arranged in overlapping relation so that fastenings driven through the overlapped edges will effectively secure the pieces together in such manner that the line of union between the pieces will be inconspicuous. It will be understood how- 30 ever that the invention may have other applications and uses.

It is an object of the invention to provide improved feeding means for the work, the 35 feeding means being preferably constructed and arranged to clamp the work firmly during the insertion of each individual fastening.

In one aspect the invention resides in 40 means for inserting fastenings into work comprising clinching means for the fastenings in association with work feeding means located at each side of the clinching means so that the work, whether of one or more 45 pieces, is properly fed and the fastenings accurately inserted along the desired line. In a preferred embodiment of the invention, the work feeding means is carried by the work support and is movable therewith as 50 the support is operated alternately to approach and recede from the work operating instrumentalities.

An important feature of the invention is found in an improved gaging means for the work whereby the location of the first fastening with respect to the edge of the work may be accurately predetermined, the construction and arrangement being preferably such that the gaging means is displaced automatically after the insertion of the first fastening to permit of unobstructed feeding of the work. In a practical form of the invention, the gaging means is so arranged as to move with the feeding means in withdrawing from gaging position.

Other objects and features of the invention will appear from the following detailed description and will be pointed out in the claims.

In the drawings,—

Fig. 1 is a view in side elevation of one embodiment of the invention;

Fig. 2 is a similar view of the fastening inserting and work feeding mechanism;

Fig. 3 is a view of the work feeding mechanism from the side opposite that shown in Fig. 2;

Fig. 4 is a detail view of portions of the fastening inserting and work feeding mechanism showing the work feeding roll in section;

Fig. 5 is a detail of the operating means for the feed roll; and

Fig. 6 is a perspective view of the gaging means for the work showing the same detached.

In the illustrative machine the fastening inserting means may be and preferably is of the type of fastening inserting mechanism shown in Patent No. 1,016,930, granted Feb. 13, 1912, on an application filed by William H. Borden.

The means for presenting the work to the fastening inserting means comprises in the construction shown in a work support designated generally by the reference character 10 and consisting of a post 12 arranged for vertical movement in guides or bearing members 14 attached to or integral with a frame 16. Normally the work support is urged into work clamping relation with the fastening inserting head by a spring 18 which surrounds the post between a fixed abutment 20 extending from the frame of

the machine and a collar 22 adjustably secured to the post. When it is desired to introduce work between the work support and the fastening guiding nozzle 22 of the 5 fastening inserting means the treadle 24 is depressed, the latter being adjustably connected to the post 12 by means of an extensible link 26 pivotally connected to both the post and the treadle. With the work in 10 position on the work support the machine may be thrown into operation upon depressing the treadle 28 which is pivoted at 30 to the frame 16 of the machine and has attached thereto at 32 the lower end of the 15 rod 34, the latter being connected at its upper end to operate the shifting mechanism for the clutch by which the loose or power pulley 36 is caused to engage the fixed clutch member 38 on the main shaft 20 of the machine. Upon rotation of the main shaft the power means for operating the work support is actuated in timed relation with the insertion of fastenings by the fastening inserting means. In the illustrative embodiment of the invention the power means for operating the work support comprises wedge members 40 of which only one is shown in Fig. 1 of the drawings, the other being exactly similar and located to 25 engage a roll on the other side of the post 12 located in line with the roll 42 with which the wedge 40 co-operates in lifting the work support to clamp the work during the insertion of fastenings. As shown, the 30 wedge 40 is slidably arranged in guideways 44 and 46 attached to or integral with the frame 16 of the machine. The means provided for operating the wedges 40 comprises preferably a bell-crank 48 fixedly secured 35 to a shaft 50 mounted in a bearing or bracket 52 at the front of the machine frame. It should be understood that the other end of the shaft 50 carries an arm rigidly attached thereto and connected to 40 the other wedge 40 to operate the same simultaneously with the operation of member 40 as disclosed in Fig. 1. Mounted in a bearing 54 at the upper end of the machine frame is a bell-crank having an arm 56 carrying a roll 58 arranged to run in a face cam in the cam member 60 fixedly attached to the main shaft 62 of the machine. The other arm 64 of the bell-crank mounted in the bearing 54 extends laterally from the 45 bearing and has rotatably mounted in its free end a member 66 through which passes freely the upper end of a rod 68 which has its lower end pivotally attached to the arm 70 of the bell-crank 48. Surrounding the 50 rod 68 between the member 66 and the adjustable collar 72 is a spring 74. It will be clear that upon rotation of the main shaft 62 the bell-crank comprising the arms 56 and 64 will be oscillated and through the 55 connecting rod 68 cause corresponding

oscillation of the bell-crank 48 and thus actuation of the wedges 40. Since the rod 68 passes freely through the member 66 at the outer end of the arm 64, bell-crank 48 will be yieldingly actuated through the 70 spring 74 which surrounds the rod 68 between the member 66 and the collar 72. However, the work support will be lifted to clamp the work firmly against the nozzle 75 22 because of the action of the wedge members 40 provided with relatively long wedging surfaces as indicated at 76.

The work supporting means 10 comprises in the construction shown an anvil member 78 carrying an anvil 80 having a flat fastening-clinching surface located directly in line with the fastening guiding nozzle 22 as shown in the drawings. To provide for adjustment of the anvil, its carrying member 78 is provided with slots 82 through which pass bolts 84 to secure the member 78 to the bracket 86 of the work support 10, a screw or bolt 88 being provided to adjust the member 78 after which it may be secured in adjusted position by tightening the bolts 84. Means is provided for feeding the work across the anvil in the intervals of fastening insertion, the said means comprising preferably a feed roll 90 mounted on a bearing extending laterally from the upper end of the post bracket 86. While the feed roll 90 may be considered operatively as one member, it is preferably made of two separate feed rolls or disks 94 secured together by screws or bolts 96, there being interposed between the disks a ratchet wheel 98 presently to be described. The feed roll 90 considered as a single member is provided with a circumferential groove 100 for the accommodation of the anvil 80 as disclosed in Fig. 4 of the drawings. Means is provided for intermittently rotating the feed roll 90, the said means in the present instance consisting of an arm 102 carried on a pivot 103 extending through the bearing for the feed roll 90. A pawl 104 arranged to project between the feed rolls or disks 94 into engagement with the ratchet wheel 98 is carried by arm 102, the pawl being held in engagement with the ratchet wheel by means of a spring 106 secured at one end to a pin 108 on the pawl and at its other end to a second pin 110 on the arm 102. It will be evident that upon oscillation of the arm 102 to the right in Fig. 2 of the drawings, the ratchet wheel 98 and the connected feed roll 94 will be rotated to cause feeding of the work. This oscillation of the arm 102 is obtained preferably by connections with the power operating means for the work support, the said connection comprising in the construction shown a link 112 pivoted at 114 to the arm 102 and at 116 to the upper end of an arm 118 fixedly attached to and extending upwardly from the shaft 50, the 120 125 130

arrangement being such that as the bell-crank 48 is operated to cause forward movement of the wedges 40 the arm 118 is moved in the reverse direction about the pivot point 50 to cause a turning movement of the arm 102 in such a direction that the pawl 104 slides over the teeth on the ratchet wheel 98, movement of the ratchet wheel under these circumstances being prevented by a retaining member 120 (Fig. 2) the operative end of which engages the teeth of the ratchet just back of the point of engagement of the pawl with the ratchet. Upon rocking movement of the bell-crank 48 in a direction to withdraw the wedges 40 from below the rolls 42 the work support is permitted to descend from position in which the work is firmly clamped to a position in which the work is yieldingly clamped through the action of the spring 18. When this movement of the bell-crank 48 takes place the arm 118 moves in the reverse direction about the pivot point 50, that is, in a forward direction to cause the arm 102 to move to the right in Figs. 1 and 2 with the result that the pawl 104 in engagement with the teeth of the ratchet wheel 98 causes rotation of the ratchet wheel and consequently a feeding operation upon the work engaged by the feed wheel 90. In order that the extent of the feeding movement may be varied as desired, the connection of the link 112 with the arm 118 is adjustable, the adjustment in the construction disclosed being provided for in a curved slot 122 along which the pivot 116 may be adjusted and secured in adjusted position. If desired a scale may be applied along the edge of the slot 122 to indicate the lengths of individual feeding movements of the feed roll in accordance with adjustment of the pivot 116 along the slot 122. By the means just described it is possible to predetermine the spacing between fastenings inserted in the work as the latter is fed automatically below the fastening inserting means.

In order that the work may be properly positioned for the insertion of the first fastening, gaging means is provided preferably in the form of a gage member 124 which is pivoted loosely on the pivots for the arm 102 and the feed wheel 90, and in the construction shown comprises a work engaging portion and two limbs 126 which are arranged to embrace the feed wheel 90. In order that the gage may be displaced after the insertion of the first fastening, it is held yieldingly in operative position preferably by means of a spring 128, an extension 130 on one of the limbs 126 being engaged by a stop 132. It is clear that from the construction shown the gage is controlled by the work in such a manner that upon withdrawal of the work at the end of fastening insertion operations, the spring automatically returns the gage to

operative position wherein the gage functions as a stop to locate the point of insertion of the first fastening in the work. As the work is fed automatically the gage is displaced laterally out of the way of the work and in the construction shown this is accomplished through the pivoting of the gage on the axis of the feed roll so that the gage moves laterally and downwardly with the feed roll 90 and is held in yielding engagement with the surface of the work until the end of the fastening inserting operations when it is immediately returned to operative position by the spring 106. It is desirable to be able to predetermine the spacing of the first staple with respect to the edge of the work and especially since pieces of work vary considerably in size and more particularly in width. Moreover, in those cases in which the spacing between fastenings is changed for any reason whatever, it is desirable to space the first fastening with respect to the edge of the work in accordance with the predetermined spacing between fastenings. For this reason the gage 124 is made adjustable as to its gaging position by means shown as consisting of an arrangement in which the stop 132 is adjustable. This adjustment being accomplished by providing a screw-threaded bolt to function as a stop, the bolt being secured in adjusted position by means of a lock nut 134.

Other features of the work support which contribute to the ease and safety of operation of the device are found in a guard presently to be described and in means arranged to co-operate with the feed roll 90 in the feeding operations, the said means consisting of a roll or rolls 136 mounted preferably one on each side of the fastening guiding nozzle 22 to turn freely on pivots attached to the nozzle or made integral therewith. These rolls are preferably so mounted as to be in vertical alinement with corresponding portions of the feed roll 90 located upon the other side of the plane of the work. The operation of the machine is illustrated in connection with the securing together of two pieces of work which have their edges beveled so that they may be brought into overlapping relation, the pieces of work being located in the same plane. In operating on work of this nature it is obviously advantageous to have two rolls above arranged to co-operate with corresponding feed rolls below or on the other side of the work so that both pieces of work will be properly controlled and fed by the feeding means. Since the lower feed rolls are secured together and operate as one roll it is clear that the two pieces of work will be fed simultaneously and as one piece of work so that there is no tendency for displacement of two pieces of work relatively to each other during the fastening inserting operations.

In thus spacing the feeding means for the two pieces of work there is provided room for the anvil or clinching means to operate to clinch the fastenings driven through the overlapping portions of the work. Even in those cases in which the work consists of a single piece or sheet there is an advantage in providing feeding rolls one on each side of the anvil since better control of the work during the feeding operation is obtained and thus fastenings will be inserted in a predetermined straight line. While in the construction shown the lower feed roll and the anvil together constitute the work support, it is clear that the bracket 86 of the work support 10 could be extended to provide work supporting surfaces on one or both sides of the lower feed roll, and thus much larger pieces of work might be presented to the machine than could readily be handled without the aid of such supporting surfaces. As now shown, the work support is designed to support the work only adjacent the line of inserted fastenings, the operative holding the outer ends of the pieces of work and finding it particularly easy to pass the work through the machine since there is no obstruction on either side of the feed wheel to interfere with free movement of the work and of the hands. Preferably, the work support 10 carries a guard member 138 to prevent the hand from coming into accidental contact with the teeth of the feed wheel 90.

In operating the machine, the operative may select a single piece of work into which fastenings are to be driven, or two pieces in overlapped relation or two pieces of work having beveled edges, in the present instance a heel part and a half-sole part, and place them with their edges overlapping in engagement with the edge gage 124, it being necessary to depress the work support by the treadle 24 in order that the work may be introduced and pressed by the work support yieldingly against the work engaging means on fastening guiding nozzle 22, which in the construction shown comprises the rollers 136. Thereafter the operative depresses the treadle 28 starting the machine, whereupon the work is automatically fed step by step through the fastening inserting plane with the result that fastenings are inserted in the work in predetermined spaced relation, thus securing the two parts of the work together. As heretofore stated the gage is displaced downwardly and rearwardly at the beginning of the feeding operation so that there is no interference with proper feeding to secure the desired spacing of fastenings.

Having fully described my invention, what I claim as new and desire to secure by Letters Patent of the United States is:

1. In a machine of the class described, fastening inserting means, means for clinching the fastenings in the work, means at each

side of the clinching means for feeding the work to the fastening inserting means, and means intermittently operative to clamp the work feeding means and the work against the inserting means during the insertion of each fastening.

2. In a machine of the class described, fastening inserting means, means comprising an anvil for clinching the fastenings in the work, and means at each side of and parallel with the anvil for feeding the work to the fastening inserting means, said anvil and feeding means being simultaneously operable to clamp the work against the inserting means during the insertion of each fastening and to release the work for each feeding operation.

3. In a machine of the class described, fastening inserting means, means for feeding the work, and a gage located beyond the point of fastening insertion for positioning the work for the first fastening and constructed and arranged to be displaced from operative position by the work positioned by the gage as said work is fed for the operation of the fastening inserting means.

4. In a machine of the class described, fastening inserting means, means for feeding the work, and a gage located beyond the plane of fastening insertion for positioning the work for the first fastening inserting operation and arranged to be movable by the work in the direction of feed to permit feeding of the work during successive fastening inserting operations.

5. In a machine of the class described, fastening inserting means, means for feeding the work, and a gage located beyond the plane of fastening insertion for positioning the work for the first fastening inserting operation and arranged to be movable with the feeding means and also independently thereof to permit feeding of the work during successive fastening inserting operations.

6. In a machine of the class described, fastening inserting means, means for feeding the work comprising a feed roll, and a gage for positioning the work mounted on the axis of said feed roll and designed to move independently of the latter about said axis during the feeding operations for the insertion of a plurality of fastenings.

7. In a machine of the class described, fastening inserting means, means for feeding the work comprising a feed roll, and a gage for positioning the work for the first fastening mounted on the axis of said feed roll and designed to move with the feed roll about said axis into inoperative position during the feeding operations for the insertion of a plurality of fastenings.

8. In a machine of the class described, fastening inserting means, means for feeding the work comprising a feed roll, and a

- gage located beyond the plane of fastening insertion and operative to position the work for the insertion of the first fastening and arranged to yield automatically, after the insertion of said fastening, in the direction of feed of the feed roll to permit feeding of the work.
9. In a machine of the class described, fastening inserting means, means for feeding the work, a gage located beyond the plane of fastening insertion and constructed and arranged for reciprocation and to be displaced by the work as the same is fed by the feeding means, and means for automatically returning the gage to operative position.
10. In a machine of the class described, fastening inserting means, means movable toward the fastening inserting means and operative to clinch the fastenings, and means for feeding the work mounted to move with the clinching means to clamp the work during the fastening inserting and clinching operations and to release the work and feed the same in the intervals of fastening insertion.
11. In a machine of the class described, fastening inserting means, means movable toward the fastening inserting means and operative to clinch the fastenings, and feed rolls rotatable independently of the clinching means to feed the work and mounted one on each side of the clinching means and movable therewith toward and from the inserting means to clamp the work during the insertion of fastenings.
12. In a machine of the class described, fastening inserting means, a plate having a flat surface maintained constantly in the line of fastening insertion for clinching the fastenings in the work, and a feed roll for feeding the work having a groove therein arranged to embrace the clinching means, said feed roll being mounted on the clinching means so as to engage the work on each side of the clinching means during the feeding operation.
13. In a machine of the class described, fastening inserting means, a clinching plate, means for reciprocating the plate from and toward the fastening inserting means for insuring proper clinching of the fastenings in the work, and a feed roll for feeding the work having a groove therein arranged to embrace the clinching means so as to engage the work on each side of the clinching means during the feeding operation and movable to clamp the work during the fastening inserting operation.
14. In a machine of the class described, fastening inserting means, comprising a fastening guiding nozzle, a movable work engaging means associated with said nozzle, and a feeding means intermittently movable toward the work-engaging means and arranged to engage the other side of the work to feed the work in co-operation with the work engaging means for the insertion of successive fastenings.
15. In a machine of the class described, fastening inserting means comprising a fastening guiding nozzle, a roll mounted on the said nozzle, and a feed roll arranged to engage the other side of the work to feed the work in co-operation with the first-mentioned roll.
16. In a machine of the class described, fastening inserting means comprising a fastening guiding nozzle, rolls mounted on the nozzle on each side thereof, and a feed roll constructed and arranged to engage the other side of the work and to co-operate with both of the first-mentioned rolls in feeding the work across the end of said nozzle.
17. In a machine of the class described, fastening inserting means comprising a fastening guiding nozzle, rolls mounted on the nozzle on each side thereof, clinching means for the fastenings, and a feed roll constructed and arranged to engage the other side of the work and to co-operate with both of the first-mentioned rolls in feeding the work across the end of said nozzle.
18. In a machine of the class described, fastening inserting means for inserting fastenings into the overlapped ends of two pieces of work, an anvil having a clinching surface maintained constantly in the line of drive of the fastenings driven into the work, and means comprising feed rolls arranged to engage the work on each side of said anvil simultaneously to feed the two pieces of work relatively to the anvil in the intervals between fastening inserting operations.
19. In a machine of the class described, fastening inserting means for inserting fastenings in the overlapped ends of two pieces of work, an anvil for clinching the fastenings driven into the work, and feed rolls arranged to move relatively to the anvil to engage the work on each side of said anvil to feed the two pieces of work together.
20. In a machine of the class described, instrumentalities for operating on work, means rotatable in one direction only and operative during each rotative movement for feeding the work and reciprocable for intermittently clamping the work during the operation of said instrumentalities, and a member for supporting the work against the thrust of said instrumentalities.
21. In a machine of the class described, fastening inserting mechanism comprising a fastening guiding nozzle, means carried by said nozzle for assisting in feeding the work, and means comprising said first men-

tioned means for clamping the work in position against the nozzle during the insertion of fastenings.

22. In a machine of the class described, fastening inserting means, means for clinching fastenings in the work, reciprocable means for operating said clinching means, and means for feeding the work arranged to be operated by said means for operating the clinching means so constructed and arranged that the feeding operation alternates with the clinching of fastenings.

23. In a machine of the class described, fastening inserting means, an anvil for clinching the fastenings driven into the work, means for operating the anvil, means for feeding the work over said anvil, and means comprising a connection between the feeding means and the anvil operating means for varying the spacing between fastenings.

24. In a machine of the class described, fastening inserting means, a work support movable toward and from the inserting means, to permit feeding of the work between fastening inserting operations, and feeding means mounted on said work support for movement therewith and operative alternately to feed the work and to clamp the work during fastening inserting operations.

25. In a machine of the class described, fastening inserting means, a work support movable toward and from the inserting means to permit feeding of the work between fastening inserting operations, means for clinching fastenings driven into the work, and feeding means on each side of the clinching means and mounted on said work support for movement therewith and operative to feed the work intermittently with the fastening inserting operations.

26. In a machine of the class described, staple fastening inserting means, a work support, a fastening-clinching anvil mounted stationary on the work support, a feed roll at one side of said anvil constructed and arranged to clamp the work against the fastening inserting means and rotatable relatively to the anvil to feed the work in the intervals of fastening insertion.

27. In a machine of the class described, fastening inserting means, a work support movable to permit of feed of the work by the fastening inserting operations, a fastening-clinching anvil mounted on the work support, a feed roll mounted on the work support at one side of said anvil and constructed and arranged to clamp the work against the fastening inserting means and to feed the work in the intervals of fastening insertion.

28. In a machine of the class described, fastening inserting means, a fastening clinching means, a feed roll having a groove to receive said clinching means so that the

work is engaged on each side of the clinching means for feeding operations thereon, and means for moving the clinching means and the feed roll simultaneously toward and from the fastening inserting means.

29. In a machine of the class described, fastening inserting means, a work support, an anvil on the work support, a feed roll having a groove to receive said anvil so that the work is engaged on each side of the anvil for feeding operations thereon, and means for moving the anvil and feed roll simultaneously toward and from the fastening inserting means.

30. In a machine of the class described, fastening inserting means, means for feeding the work constructed and arranged to vary the spacing between fastenings, a gage for positioning the work for the insertion of the first fastening, said gage being work-controlled to be movable out of the path of the work and means for varying the position of the gage so that the distance of the first fastening from the edge of the work may be made to vary with the change in the spacing of the fastenings.

31. In a machine of the class described, fastening inserting means, means for feeding the work constructed and arranged to vary the spacing between fastenings, a gage for positioning the work for the insertion of the first fastening and displaceable by the work after the insertion of said fastening, and means for varying the position of the gage so that the distance of the first fastening from the edge of the work may be made to vary with the change in the spacing of the fastenings.

32. In a machine of the class described, fastening inserting means, a work support, an anvil carried by said work support, a feed roll for feeding the work across said anvil, and power means for causing said feed roll to engage the work positively to clamp the same against the inserting means during insertion of fastenings.

33. In a machine of the class described, fastening inserting means, a work support, an anvil carried by said work support, a feed roll for feeding the work across said anvil, and power means for causing said feed roll and anvil to engage the work positively to clamp the work against the inserting means during insertion of fastenings.

34. In a machine of the class described, fastening inserting means, a work support, means for yieldingly urging the work support into work clamping relation to the work, a feed roll carried by said work support and operative to feed the work while the work support is maintained in yielding work clamping relation to the work, and power means for causing the feed roll to clamp the work more firmly during the insertion of fastenings.

35. In a machine of the class described, fastening inserting means comprising a fastening guiding nozzle provided with a roll for engaging the work, a work support, 5 means for yieldingly urging the work support into work clamping relation to the work, a feed roll carried by said work support and operative to feed the work while the work support is maintained in yielding 10 work clamping relation to the work, and power means for causing the feed roll to clamp the work against the roll on the nozzle during the insertion of fastenings.
36. In a machine of the class described, 15 staple fastening inserting means, an anvil for clinching the fastenings inserted into the work, and feed rolls constructed and arranged to engage two pieces of work one at each side of the anvil and to feed the work from front to rear of the machine, the construction and arrangement being such that the cross bars of the staples lie parallel with each other in a direction transverse of the line of union of the two pieces of work. 20
- 25 In testimony whereof I have signed my name to this specification.

FRED L. MACKENZIE.
